UNITED STATES PATENT OFFICE.

M. A. WOODSIDE, OF GEORGETOWN, CALIFORNIA.

IMPROVED MACHINE FOR WASHING ORES.

Specification forming part of Letters Patent No. 58,931, dated October 16, 1866

To all whom it may concern:

Be it known that I, MILTON A. WOODSIDE, of Georgetown, El Dorado county, State of California, have invented a new and Improved Machine for Saving Gold and Sulphurets, called "Woodside's Endless Blanket," and I do hereby declare that the following is a full, clear, and exact description of the construction and operation of the same, reference being had to the drawings making part of this specification, in which—

Figure 1 is a side elevation with a section through the center longitudinally, shown by dotted lines; Fig. 2, a plan; Fig. 3, an end view from rear, driving-pulleys removed.

The nature of my invention consists of a machine driven by pulleys having an endless blanket of canvas or other material, the ore being introduced upon the blanket through a perforated box placed across the machine. A perforated pipe is also placed across the machine above the ore-box, through which jets of water play upon the blanket, which carry off the light sand and débris, leaving the gold and sulphurets, which are carried in opposite direction (the blanket being revolved at an incline) over the upper end, where they come in contact with a brush, which sweeps them off into a box.

By this arrangement the necessity of frequently cleaning and washing the blanket is obviated, and a greater proportion of the gold and sulphurets is saved.

To enable others skilled in the art to make and use my improved endless blanket, I will proceed to describe its construction and operation.

Referring to the drawings, A A are the sides of the machine, fastened to an inclined tablet, B, by screws or bolts M M.

Around the rollers C C traverses the endless blanket H, of canvas or other material, with narrow leather or rubber sides or edges G G.

The box I, pierced with fine holes, receives the pulp from the battery or stamps, and dis-

tributes it upon the revolving blanket. A pipe, J, having fine jets beneath, serves to admit sufficient water upon the blanket to distribute the pulp and carry off the sand down the upper slope of the blanket.

Beneath the blanket a roller, K, carrying stiff brushes L L, continually revolves during the action of the machine, and disengages the sulphurets from the blanket, causing them to fall into the box P, upon the edge of which the machine is placed, being kept in position by the notch O in the lower edges.

Material is communicated from the power used to the pulley E, the shaft of which carries the brush-roller K.

By a belt, F, the pulley D, which drives the light hand-roller C, receives motion.

In operation, power is applied to the pulley E by a belt and the machine set in motion. The rollers C C and blanket H move in the direction of the arrows. The pulp is received from the mill into the box I, and is thence distributed upon H. The strips G G prevent the pulp from running off the edges. The streams of water from the pipe J carry the light sand off the lower end of the blanket. The heavy sulphurets remain upon it and are carried over the upper end, and until they come in contact with the brushes L L, which sweep them off into the box P.

Having thus described my invention, what I claim, and desire to secure by Letters Patent, is—

1. The endless blanket H and revolving brush K, when arranged substantially as described, and for the purpose set forth.

2. The perforated feed-box I and water-pipe J, substantially as specified, and for the purpose set forth.

In witness whereof I have hereunto set my hand and seal this 27th day of October, A. D. 1865.

M. A. WOODSIDE. [L. S.]
